WATER SCOOP FOR BOATS

Hubert Scott-Paine, Southampton, England

Application April 24, 1940, Serial No. 331,319
In Great Britain June 5, 1939

1 Claim. (Cl. 114—185)

This invention concerns improvements in or relating to water scoops for boats for the purpose of conducting water into and out of the boat.

The invention comprises, in or for a boat, particularly a high-speed boat, a water scoop comprising a pipe having an oblique flange to secure the scoop to the boat hull, and an open end, slightly less oblique than the flange, extending through the flange from a point in or near the general plane of the flange.

The invention is particularly applicable to a high-speed boat having a hard chine hull, in which case the scoop is arranged on the V-shaped bottom of the hull at a part which is covered by a streamlined flow of water at all speeds of the boat. The scoop may be used as a pressure scoop, in which case the pipe is arranged to slope upwardly aft from the flange so that the edge or lip of the pipe which projects into the water faces the flow of water when the boat is moving forward and directs the water within the boat. Alternatively, the scoop may be used as a suction scoop, in which case the pipe slopes upwardly forward of the boat so that the scoop operates as a self-bailer fitting drawing water from within the boat.

In order to provide a construction which offers a minimum of resistance to the passage of the boat through the water, the scoop is preferably provided with a streamlined fairing between the projecting end of the pipe-opening and the flange. In addition, the pipe is smoothly curved upwardly from its open end, and the wall of the pipe, opposite its projecting edge or lip, may be curved to meet the flange tangentially so as to facilitate a smooth flow of water through the pipe.

In the accompanying drawing which illustrates one embodiment of this invention:

Figure 1 is an elevation in section of the scoop,
Figure 2 is an underside view of the scoop,

Figure 3 is a section on the line 3—3 of Figure 1, and

Figure 4 is a section on the line 4—4 of Figure 1.

Like reference characters indicate like parts throughout the drawing.

Referring to the drawing, the scoop consists of a circular pipe 10, the upper end 11 of which is substantially vertical and the lower end 13 is curved in the fore-and-aft plane of the vessel. The lower end of the pipe is integral with a flange 12 which is secured to the bottom of the boat. This flange 12 is set obliquely to the lower

end of the pipe, and the open end of the pipe 13 in the neighbourhood of the flange is also oblique to the axis of the pipe at this point, its obliquity being somewhat less than that of the flange.

One edge 14 of the pipe thereby projects below the flange 12 and the opposite side of the pipe at 15 is formed to an easy curve tangential to the face of the flange.

The part 14 of the pipe 10 which extends below the flange 12 and there forms a cowl-like protuberance at the lower end 13 of the pipe is provided with a streamlined fairing 16, this being suitably curved both fore-and-aft and laterally to ensure an easy flow of the water over it. Conveniently, the flange is of uniform thickness as shown in Figure 1 so that the centre portion is dished near the edge 14 of the pipe.

It will be seen that with this arrangement the open end of the pipe projects slightly below the bottom of the boat and in the case of pressure scoops this opening faces forward and when it is to be used as a suction scoop it faces aft.

A grid or grating is provided across the lower open end of the pipe and is conveniently constituted by a number of bars 17 lying in a fore-and-aft direction so as to offer a minimum resistance to the motion of the boat through the water. For this purpose also they may be tapered along their length from the leading to the trailing edge, and for this purpose the taper will be in opposite directions on suction and pressure scoops.

It will be appreciated that as the pipe meets the flange obliquely, it provides an open mouth of large area and the pipe is shaped at its open end so as to provide a substantially rectangular opening. In addition, there is only a very small edge projecting into the water, but as the bottom surface of a high-speed boat, to which the scoop is fitted, is a high pressure surface, there is a

sufficient pressure difference when the boat is in motion to cause circulation of the water through the pipe, and the cross-sectional area of the pipe is such as to provide the required passage for the necessary quantity of water. The scoop thus offers a minimum of resistance to the passage of the boat through the water, which is an important feature in high-speed boats. In addition, the small extent of projection of the scoop below the boat bottom is of advantage when launching cradles are used, since the scoop is not likely to be damaged if the boat should come to rest in a position other than that provided for by the spacing of the cradle members.

The upper end 11 of the pipe may be screw-threaded or formed in any other desired manner

according to the coupling which is to be used with it, and ordinarily a control valve will be provided in the piping adjacent to the scoop. This valve may be of any convenient type and may be arranged for remote control if so desired. The piping connected with the scoop will, of course, be varied according to the purposes for which the scoop is to be used.

I claim:

A water scoop for a motor boat comprising a 10 pipe having a wall and a flange-like body integral therewith, the pipe wall defining a curved conduit having an open end, the flange-like body disposed in an oblique relation to the axis of the

conduit at its open end and the open end lying in the general plane of the flange-like body, one portion of the wall terminating in the general plane of said flange-like body and the opposite portion of said wall terminating out of said plane and there forming a cowl-like protuberance having at one side thereof a fairing surface tapering toward and terminating approximately in the plane of the flange-like body, a plurality of bars extending from the extremity of the protuberance across the open end of said conduit thereby constituting a grid for said conduit preventing ingress of debris to said protuberance.

HUBERT SCOTT-PAINE.
